UNITED STATES PATENT OFFICE.

ROBERT A. WILLIAMS AND JOHN BRAGG, OF CLEVELAND, OHIO.

APPARATUS FOR EXTRACTING PARAFFINE FROM OILS.

SPECIFICATION forming part of Letters Patent No. 317,060, dated May 5, 1885.

Application filed December 8, 1884. (No model.)

To all whom it may concern:

Be it known that we, ROBERT A. WILLIAMS and JOHN BRAGG, of Cleveland, Cuyahoga county, and State of Ohio, have jointly invented a certain Improved Apparatus for Extracting Paraffine from Oils, of which the following is a specification.

The special use of the said apparatus and process is for chilling or freezing paraffinized oils for extracting therefrom paraffine.

The construction of the apparatus and the practical operation thereof with reference to the process are described in the following specification, and illustrated in the annexed drawings, making part of the same.

Figure 1 represents a vertical transverse sectional view of the apparatus. Fig. 2 shows a plan view of the apparatus, a portion of the cover of which is represented as broken away that certain interior parts of the apparatus may be seen.

Like letters denote like parts in the drawings.

As shown in the drawings, A represents a cylindrical - shape tank, preferably made of wood, of any desirable holding capacity. B is the cover, and C the bottom.

Vertically and centrally through the tank passes a tubular shaft, D, the foot of which has its bearing in the step E, forming a portion of a stuffing-box, F, through which the shaft passes, and by which it is made tight in connection with the conductor G, passing through the bottom of the tank, as seen in Fig. 1. In said figure it will be observed that the upper end of the conductor G terminates in a cylinder-case, H, fixed centrally in the tank A, but not in open communication therewith. Said case is preferably made of sheet metal and of the shape shown, substantially as seen in the drawings. It will be noticed that the bottom of the case H is dishing, and opens into the conductor G, the outlet of the case. The upper end of the tubular shaft D projects through the top of the tank A, and is made close-fitting in its relation therewith by means of a stuffing-box, I, which is or may be like those in ordinary use.

J is a crown-wheel secured to the shaft D, and by which the shaft is revolved by the wheel engagement with the pinion K on the

shaft L, having its bearings in the standards M. The shaft is operated by the pulleys N, to which power is applied by a belt. (Not shown.)

To the tubular shaft D above alluded to is secured a hollow freezer, O, in shape similar to the case H, and inclosed thereby, as seen in Fig. 1, in which it will be noticed that between the said case and the freezer is a considerable space for a purpose hereinafter shown. 55 The said freezer O is preferably made of sheet metal, and is in open communication with the tubular shaft by means of an induction-aperture, a, and one eduction-aperture, b, respectively on the sides of the dividing plate or partition P, so that the two openings or ports have not a direct communication one with the other, but indirectly through the freezer O, as hereinafter shown.

Q is a dish secured to the tubular shaft, and 70 R is a tube penetrating the top of the tank and terminating in communication with the dish Q.

S is an adjustable scraper adapted to fit the upper surface of the freezer, and to which it is adjusted more or less distant therefrom by the lever T, to which the scraper is attached by the rod U, working in a stuffing-box that it may be close-fitting in its passage through the top of the tank. A' is also a scraper 80 adapted to the surface of the case H. Said scraper is secured to the tubular shaft and revolves with it.

In the conductor G above referred to is a spiral conveyer, B', Fig. 1, surrounding the 85 tubular shaft D, and revolves therewith.

C' is a pipe leading from a vessel, D', containing a refrigerant fluid, to the tubular shaft, in the upper end of which shaft it terminates, as seen at E' in Fig. 1.

From the pipe C' proceeds a pipe, F', down to the bottom of the tank A, into which it projects and extends therein near to the center. Said pipe F' is in open communication with the tank A by means of the perforations c in 95 the side of the pipe, as seen in the drawings.

G' is a pipe the upper end of which is in open relation with the upper end or top of the tank A, whereas the opposite end of the said pipe terminates in a receiving-tank, H'. Said 100 pipe

pipe G' is also in open relation with the tubular shaft D by means of the interposed connection J'.

Having described the construction and arrangement of the aforesaid apparatus, its operation is substantially as follows: The tank A is charged with a refrigerant fluid of any suitable nature from the vessel D', which flows by gravity therefrom into the tank through the pipe F' (seen in Fig. 1) and perforations c. The refrigerant flows from the tank through the eduction-pipe G', and is discharged into the receiving-tank H', from which it is again returned by a pump (not shown in the drawings) to the vessel D', or otherwise disposed of. By this means is established a current of refrigerant fluid through the tank, in which fluid the case H is wholly immersed, and thereby reduced to a low and constant degree of temperature, and not materially influenced by the external air, or being wholly surrounded by the refrigerant-fluid in the tank A, as above mentioned. The freezer O is also filled with the refrigerant fluid, the fluid passing from the vessel D' through the pipe C', and discharges into the end of the tubular shaft, down which it flows to the port a and enters the freezer. The refrigerant escapes from the freezer through the eduction-port b into the tubular shaft D on the opposite side of the partition P, and flows down it to the pipe G', thence to the receiving-tank H', and is returned to the vessel D' along with the fluid from the tank A, above referred to. From the above it will be obvious that a current of refrigerant fluid is established through the freezer, which, as in the former instance, is reduced to a low degree of temperature, and for being inclosed in the case H, and the case immersed in the refrigerant fluid contained in the tank A, as above described. The freezer, not being in direct contact with the external atmosphere, is but little influenced thereby, so that the paraffine-oil when discharged upon the freezer is immediately chilled or frozen, for the purpose specified. The oil to be chilled is conveyed into the freezer by the induction oil-pipe R put in communication with an oil-tank. (Not shown in the drawings.) Said tank is so situated that the oil will flow therefrom by gravity and discharge into the dish Q, before mentioned. While the oil is discharging into the dish Q the tubular shaft is revolved by the mechanism above described. With the shaft revolves the freezer O, and also the dish Q. From said dish the oil, by centrifugal force, is spread over the surface of the freezer, upon which it is immediately chilled or frozen. The frozen material is removed therefrom by the scraper S, which is pushed down into the frozen oil by the lever T from time to time, as the accumulation of the chilled oil upon the surface of the freezer may require, for its removal. The scraper may be allowed to remain in one position near the surface of the freezer, and thereby scrape off the chilled oil continu-

ously. The material thus scraped from the surface of the freezer O falls upon the inclined bottom of the case H, and that it may not lodge there it is scraped therefrom into the conductor G by the scraper A', and that it may not fill up and choke the passage-way of the conductor it is forced down by the spiral conveyer B' to the chute K', from which it is taken and prepared for the press for expressing the oil from the frozen mass in the usual way.

It will be obvious from the above that the oil in its passage through the apparatus is subjected to the influence of several chilling surfaces, first, upon the surface of the freezer O, upon which it falls, and also from the chilling influence of the top of the case, and when the chilled mass is scraped off from the freezer it falls upon the cold freezing-surface of the bottom of the case H, and at the same time continued under the chilling influence of the bottom of the freezer, so that the material is thoroughly chilled or frozen on leaving the apparatus, which is kept from being warmed by the large body of refrigerant in the tank A, which is constantly being renewed without stopping the working of the apparatus for that purpose, as the freezing of the oil and supplying the same to the freezer is automatically and constantly performed; hence there is no loss of time by delay in working the apparatus.

What we claim as our improvement, and desire to secure by Letters Patent, is—

1. In an apparatus for chilling or freezing oils, the combination of the tank A, the case H, constructed in the form described, the revolving freezer O, having its top and bottom dished and attached to the tubular shaft D, having the induction and eduction ports a and b, separated by the partition P, and the refrigerant-conductor C', substantially as and for the purpose described.

2. The induction refrigerant-pipes C' and F', arranged in relation to and in combination with the tubular shaft, and refrigerant-tank A, and supplying refrigerant-vessel D', substantially as described, and for the purpose set forth.

3. The refrigerant-eduction pipe G', arranged in relation to the refrigerant-tank A, outlet J', of the tubular shaft and receiving-tank H', pipes C' and F', for the purpose specified, and substantially as described.

4. An apparatus for freezing or cooling oils, consisting of tank A, case H, revolving freezer O, secured to the tubular shaft D, having the induction and eduction ports a and b, separated by the partition P, the exterior scraper, S, and interior scraper, A', the spiral conductor B', the oil-supply pipe R, and saucer Q, induction-pipes C' and F', eduction-pipe G', outlet-pipe J', and reservoir H', all constructed and combined substantially as and for the purpose described.

5. An apparatus for freezing oils, consisting of a refrigerant-tank, A, case H, having

therein a horizontally-revolving freezer secured to a tubular shaft provided with induction and eduction ports separated from each other by a partition, P, adjustable scraper S,
5 and revolving scraper A', arranged in relation to the spiral conveyer, oil-induction pipe R, refrigerant-induction pipes C' F', and eduction refrigerant-pipe G', constructed and arranged to co-operate substantially as de-
10 scribed, and for the purpose specified.

In testimony whereof we affix our signatures in presence of two witnesses.
